UNITED STATES PATENT OFFICE.

ABEL D. TYLER, JR., OF BROCKTON, MASSACHUSETTS.

COMBINED BOOT OR SHOE TREE AND TOP-STRETCHER.

SPECIFICATION forming part of Letters Patent No. 615,002, dated November 29, 1898.

Application filed March 26, 1898. Serial No. 675,343. (No model.)

To all whom it may concern:

Be it known that I, ABEL D. TYLER, Jr., of Brockton, in the county of Plymouth and State of Massachusetts, have invented an Improvement in a Combined Boot or Shoe Tree and Top-Stretcher, of which the following is a specification.

Referring to the accompanying drawings, Figure 1 is a side elevation, and Fig. 2 a top plan view, of one form of my invention. Fig. 3 is a sectional view in line 3 3 of Fig. 1. Fig. 4 shows a slight modification of the means for engaging the upper front corners of a lace-shoe top. Fig. 5 shows my invention adapted for use on button-boots. Figs. 6, 7, and 8 show modifications, Fig. 7 being a sectional view on line 7 7 of Fig. 6.

The object of my invention is to mechanically stretch a shoe-top upwardly and forwardly on the tree. Heretofore this work has been done by hand, the operator seizing an upper fore corner of the top and pulling it tight on the tree while ironing or treeing the top. Having finished one side or ankle portion of the top, the operator then seizes the other upper fore corner of the top and pulls the top upwardly and forwardly of the tree. This handwork is objectionable both on account of the inconvenience of holding the top corners by one hand while applying the iron with the other hand, and on account of the unequal stretch sometimes imparted to the top which is set in shape by the ironing or treeing, and on account of the ineffectual removal of the wrinkles, which frequently reappear, sometimes before leaving the factory and sometimes later.

In the drawings illustrating the principle of my invention and the best mode now known to me of applying that principle, A is a "boot-tree" of known construction and is one of the multitudinous forms of such apparatus.

B is my new top-stretcher, such a device being wholly new with me both of itself and in combination with the tree. In this present construction stretcher B is made up of a Y-shaped piece the arms b b of which straddle leg a of the tree and are pivoted thereto, the free ends of the arms b b extending toward 45 of leg a. Shank b' of this Y-shaped piece is chambered lengthwise and provided with an endwise-movable tooth b², which projects

slightly between the arms b b and is adapted to engage the opposed serrations a' on the rear of leg a. The shank b³ of tooth is surrounded by a coiled spring b⁴, which holds tooth b³ normally in engagement with a serration a' to lock the stretcher in fixed relation to the tree. Spring b⁴ is mounted between projection b⁵ of shank b³ and the outer end b⁶ of the chambered shank b'. The outer end of the tooth-shank b² projects from the chambered shank, and a pull thereon unlocks the tooth from the serrations, so that the free ends of the arms b b may be swung toward 60 or away from the ankle and instep portions of the tree. The free ends of the arms b b are each provided with an extension b⁷, preferably in the form of a coiled spring, and the free end of each extension b⁷ is provided with 65 a suitable device b⁸ for connection with the upper front corner of a lace-shoe. In Figs. 1 and 2 this device is a ring adapted to engage the lacing-hook x on the lace-shoe x'; but where lacing-eyelets are used instead of lacing-studs the device b⁸ may take the form of 70 a hook adapted to hook into the eyelet. 75

If desired, a suitable clamp—such, for example, as an ordinary necktie or garter clasp—may be substituted for the ring or hook form 80 of device b⁸; but where such a clamp or clasp is used it is best to face its jaws with rubber or the like to prevent abrasion of the tops. Any other desired form of device b⁸ may be used. When a lace-shoe is on the tree, the 85 devices b⁸ are connected to the upper front corners of the tops x². The shank of the stretcher is then pressed toward the heel of the tree, and the tops x² thereby stretched forwardly and upwardly over the ankle and side 90 portions of the tree and smoothly over the tree above its heel portion. The mode of stretching of the leather smooths out the leather uniformly on both sides at the same time and pulls out the heavier wrinkles commonly occurring at the junction of the tops with the rearwardly-extending wings x³ of the vamp at and near x⁴. Thus stretched the top is ready to be rubbed with the hot iron or other device. The workman now has both hands free and 95 labors to better advantage than heretofore and the top is stretched more uniformly and thoroughly than heretofore, and the stretching and ironing are more efficacious than here- 100

tofore in preventing the return of the wrinkles and preserving the tops in correct shape.

The stretcher B may be combined in various ways with the different forms of boot-trees 5 for many years in common use, and I do not intend to limit my invention to any particular embodiment.

In Fig. 5, where the shoe is a button-shoe and one portion of the top laps over the instep, 10 the device b^8 is a clasp made up of the rubber-faced jaws 1 and 2, jaw 2 being in the form of a lever.

It is sometimes desirable to pull the tops upwardly at more than one point, and while 15 more than one extension b^7 may be carried by the pivoted Y-shaped lever b I may sometimes employ the reciprocating frame Q, as shown in the modifications of Figs. 6, 7, and 8. Herein frame Q has a central enlargement

20 encircling the leg of the boot-tree with diametrically-opposed chambered wings q q , each containing a spring-controlling tooth, which engages opposed serrations q' on the leg of the boot-tree. Leg a is provided with guideways 25 q^2 q^3 , one on each side of the leg, and in these guideways the inwardly-projecting pins of frame Q slide when the frame is adjusted by manipulating the spring-controlled teeth.

Any desired number of clamp-carriers Q' may 30 be attached to frame Q, the clamps (of any

desired form) being connected with the shoe-tops. By sliding frame Q upwardly the tops are stretched at one or more desired points.

What I claim is—

1. The combination of a boot or shoe tree 35 with a stretcher which is provided with means to engage a shoe-top, said means being movable forwardly and upwardly away from the ankle portion of the tree.

2. The combination with a boot or shoe 40 provided with a serrated surface of a stretcher pivoted on the leg portion of the tree and provided with spring extensions and thereto connected top-engaging devices, and with a spring-controlled tooth which engages said 45 serrations.

3. The combination of a boot or shoe tree with an adjustable frame mounted on the tree, above the foot portion of the tree, and movable in relation to said foot portion; and a 50 device, carried by said frame, for connecting the frame with a boot or shoe upper.

In testimony whereof I have signed my name to this specification, in the presence of two subscribing witnesses, on this 9th day of 55 March, A. D. 1898.

ABEL D. TYLER, JR.
